UNITED STATES PATENT OFFICE.

MARIAN CURRY TEBBETTS, OF PITTSBURGH, PENNSYLVANIA.

DESIGN FOR A DOLL.

Application filed January 6, 1922. Serial No. 72. Term of patent 7 years.

To all whom it may concern:

Be it known that I, MARIAN CURRY TEBBETTS, a citizen of the United States, residing at Pittsburgh, in the county of Allegheny and State of Pennsylvania, have invented a new, original, and ornamental Design for a Doll, of which the following is a specification, reference being had to the accompanying drawing, forming part thereof.

The figure of the drawing is a front view of a doll constituting my new design.

I claim:

The ornamental design for a doll, as shown.

MARIAN CURRY TEBBETTS.
